UNITED STATES PATENT OFFICE.

WILHELM BRUESS, OF SANDUSKY, OHIO.

DESIGN FOR AN AUTOMOBILE-TIRE.

51,917.

Specification for Design.

Patented Apr. 2, 1918.

Application filed February 6, 1918. Serial No. 215,707. Term of patent 14 years.

To all whom it may concern:

Be it known that I, WILHELM BRUESS, a citizen of the United States, residing at Sandusky, in the county of Erie and State of Ohio, have invented a new, original, and ornamental Design for Automobile-Tires, of which the following is a specification, reference being had to the accompanying drawing, forming a part thereof.

In the drawing the figure is a perspective view of an automobile tire, showing my new design.

I claim:

The ornamental design for an automobile tire as shown.

WILHELM BRUESS.
